(57) **CLAIM**

The ornamental design for a UAV remote control mount adapter apparatus, as shown and described.

DESCRIPTION

FIG. 1 is an upper perspective view showing a first embodiment of our new UAV remote control mount adapter apparatus.

FIG. 2 is a lower perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is an upper perspective exploded view thereof;

FIG. 10 is a lower perspective exploded view thereof;

FIG. 11 is a right side view thereof, as engaged with an exemplary tripod and an exemplary UAV remote control; FIG. 12 is a perspective view showing a second embodiment of our new UAV remote control mount adapter apparatus design;

FIG. 13 is a lower perspective view thereof;

FIG. 14 is a front view thereof;

FIG. 15 is a rear view thereof;

FIG. 16 is a right side view thereof;

FIG. 17 is a left side view thereof;

FIG. 18 is a top view thereof;

FIG. 19 is a bottom view thereof; and,

FIG. 20 is a right side view thereof, as engaged with an exemplary tripod and an exemplary UAV remote control.

The broken lines shown are included only for the purpose of illustrating unclaimed portions of the article along with environmental subject matter, and form no part of the claimed design.

1 Claim, 10 Drawing Sheets
